BAKING DISH

Gunnar Cyren, Gavle, Sweden, assignor to Dansk International Designs Ltd., Mount Kisco, N.Y.

Filed Feb. 19, 1974, Ser. No. 443,929

Term of patent 14 years

Int. Cl. D7—01

U.S. Cl. D7—21

FIG. 1

FIG. 1 is a top plan view of a baking dish showing my new design;

FIG. 2 is a side elevational view thereof;

FIG. 3 is a bottom plan view thereof; and

FIG. 4 is an end elevational view thereof.

I claim:

The ornamental design for a baking dish, as shown.
